UNITED STATES PATENT OFFICE.

EUGENE A. CORY, OF PROVIDENCE, RHODE ISLAND.

DESIGN FOR A WATCH-CHAIN.

SPECIFICATION forming part of Design No. 16,313, dated October 6, 1885.

Application filed July 1, 1885. Serial No. 170,424. Term of patent 7 years.

To all whom it may concern:

Be it known that I, EUGENE A. CORY, a citizen of the United States, residing at Providence, in the county of Providence and State of Rhode Island, have invented and produced a new and original Design for Watch-Chains; and I do hereby declare the following to be a full, clear, and exact description of the invention, reference being had to the accompanying drawings, and to letters or figures of reference marked thereon, which form a part of this specification.

This invention relates to a design for watch-chains; and it consists of links having the configuration of a pair of crossed base-ball bats, links representing each a base-ball, and links having any well-known shape—as, for example, round, oval, curb, double-curb, rectangular, &c.—the whole being arranged to form a watch-chain, the bar thereof being one of said double-bat links.

In the accompanying drawings, Figure 1 represents a perspective view of a watch-chain embodying my design, and Fig. 2 is a similar view, the design being essentially the same, except that a link representing a base-ball cap is substituted for one of the base-ball links.

In the drawings, B designates an element of the design, consisting of the link representing

and having the contour of two crossed base-ball bats. C indicates another element or link of the design, the same having the shape of a base-ball.

D, Fig. 2, indicates a link representing and having the form of a base-ball cap.

The links forming the double bats B, balls C, and cap D, may be arranged in relation to each other to form a watch-chain, as represented in the drawings, said links at the same time being combined with intermediate links. These latter, however, form no essential feature of my present design.

Having thus described my invention, what I claim as my design, and desire to secure by United States Letters Patent, is—

The design for a watch-chain and bar herein shown and described, the same consisting of the bar having the shape of two crossed base-ball bats, link B, representing two crossed base-ball bats, ball C, and cap D, substantially as set forth.

In testimony whereof I have affixed my signature in presence of two witnesses.

EUGENE A. CORY.
